FIG. 2.

FIG. 1.

Des. 183,468

PAGE 2

Fig. 1 is a perspective view, on a reduced scale, of an ironing table showing my new design;

Fig. 2 is a bottom plan view thereof;

Figs. 3 and 4 are side and end elevational views, respectively, of the ironing table;

Fig. 5 is a top plan view thereof;

Fig. 6 is an enlarged detail view of the portion within the circle "6" of Fig. 5;

Fig. 7 is a cross section on the line 7—7 of Fig. 6; and

Fig. 8 is a cross section on the line 8—8 of Fig. 7.

The punched details cover the entire table top but portions of them are omitted for convenience of illustration.

I claim:

The ornamental design for an ironing table, as shown and described.
